UNITED STATES PATENT OFFICE.

FREDERICK D. STALFORD, OF FREDERICK, OKLAHOMA.

CRUDE-OIL BURNER.

941,285.

Specification of Letters Patent. Patented Nov. 23, 1909.

Application filed September 10, 1909. Serial No. 517,085.

To all whom it may concern:

Be it known that I, FREDERICK D. STALFORD, citizen of the United States, residing at Frederick, in the county of Tillman and

5 State of Oklahoma, have invented certain new and useful Improvements in Crude-Oil Burners, of which the following is a specification.

This invention relates to certain new and 10 useful improvements in burners for crude oil or similar liquid fuels and particularly to improvements on the apparatus shown in my pending application, Serial No. 516,340, filed on the 7th day of September 1909.

15 The general object of the invention is to provide a simple, durable and efficient construction of crude oil burner which may be placed in the fire-pot of any ordinary stove which in its operation will effectively consume the fuel and secure or produce a hot flame, and it includes a plurality of troughs which may be moved successively into operative position as the troughs become corroded or otherwise unfit for use.

25 The particular object of this improvement of my pending application is to provide means whereby the oil may be more economically burned when a low fire is desired, these means, however, being so arranged that 30 a considerably greater heat may be secured when required.

To this end the invention consists in the arrangement of the parts and details of construction described in the following specification and particularly set forth in the claims appended.

35 For a full understanding of the invention reference is to be had to the following description and accompanying drawings, in 40 which:

Figure 1 is a perspective view of my burner. Fig. 2 is a transverse sectional view thereof showing the same in place within the fire-box of a stove. Fig. 3 is a longitudinal section of the burner, the partition plates being omitted and Fig. 4 is a transverse section enlarged of the central portion of the burner showing certain details of construction.

45 Corresponding and like parts are referred to in the following description and indicated in all the views of the accompanying drawings by the same reference characters.

50 My improved crude oil burner includes a revoluble body portion which comprises two heads 1 which are preferably circular,

and any desired number of substantially radiating partition plates 2 secured at their ends to the heads and thus forming a plurality of troughs or pockets 3 in which the crude oil or similar liquid fluid is intended to be burned. The revoluble body portion also includes a central longitudinal shaft which is journaled at its ends as indicated at 4 in bearings formed for it in standards 60 or uprights 5 which form part of a supporting frame. This frame is preferably supported on laterally extending feet 6 connected to each other by a bracing cross-bar 7. The improved burner is thus adapted 65 to rest upon the grate B of a stove A of any usual type.

8 designates an air induction hood. This is preferably provided with a tapering tubular neck 9, one end of which is formed 75 with damper regulated openings 10 through which varying proportions of air may be admitted into the interior of the hood, this portion of the device being thus adapted to be mounted in and protrude from the ordinary damper opening of a stove. The end of the neck 9 is also formed with a central opening through which the fuel supply pipe 11 passes, said pipe being connected at one end to any suitable source of oil supply such 80 as a tank, (not shown). The inner end of the supply pipe 11 has a cross-arm or cross-pipe 14 connected to it, this pipe being provided with a plurality of downwardly opening orifices 15 through which the crude oil 85 drops into that particular trough 3 which is uppermost. The pipe 14 is supported at its ends in the upper ends of the standard 5, as indicated at 16. Preferably the hood 8 is supported at its inner end by resting upon 90 the pipe 14, and the hood at its inner extremity is formed with the oppositely extending flared flanges 17 designed to extend partially over and inclose or partially cover the top of the uppermost trough 3 in the 95 operation of the device so that the air passing into the trough 3 from the hood 8 will be detained within the trough sufficiently to become thoroughly commingled with the fuel dropping from the orifices 15, whereby 100 combustion will be more thoroughly promoted. These outwardly projecting flanges 17 also act as directing wings directing the flame on each side outwardly between the lateral walls 2 of the troughs 3, and the 105 edges of the wings and flanges 17 and thus causing an upward blast of air and flame.

Located longitudinally within each of the troughs and midway between the walls 2 are a plurality of cups or receptacles 18, these cups being carried or being attached at their bases to a longitudinally extending central bar 19 which is formed in one piece with the plates 2 or is separately made and to which the plates 2 are attached. These cups or receptacles 18 are so arranged within the troughs that when any one trough is turned so as to be immediately beneath the pipe 14, the receptacles 18 will be immediately beneath the orifices 15 in the tube 14 and thus the fuel oil passing into the transverse pipe 14 will drip into the cups 18. If the supply of oil is relatively moderate the oil will be consumed in these cups 18 at about the same rate as it drips into the cups and hence the fuel oil will not overflow the edges of the cups and fill the troughs. If, however, the supply of oil is greater than can be consumed in the cups, the oil will overflow the receptacles or cups 18 and fill the lower portion of the troughs. The purpose of this will be stated hereafter. While I may support these cups or receptacles 18 in any suitable manner within the troughs I have shown two means of accomplishing this end. In the construction shown in Fig. 2 the lower extremities of the cups are screw-threaded and inserted in sockets 21 formed upon the bar 19. In Fig. 4, however, the bar 19 is shown as formed with screw-threaded bores on its sides, and each of the cups has passing through it the attaching screw 22 whose lower end enters the screw-threaded sockets or bores. The outer end of the screw is countersunk into the bottom of the cup or receptacle. I do not wish to limit myself, however, to any specific manner of supporting these cups or receptacles within the compartments or troughs.

The operation of my improved burner will be apparent. The device is supported within the fire-box of a kitchen range or other stove as fully illustrated in my prior application before referred to. The revoluble body portion is turned as by a handle applied to the square end 4^a of the shaft 4, so that one of the troughs or compartments 3 is brought into position immediately beneath the discharge end of the hood 8 and of course immediately beneath the perforations 15 of the pipe 14. The oil is then permitted to flow into the pipe 11 and after it drops through the orifices 15 and is lighted will be met by the down draft of air passing into and through the hood 8 so that the fuel will become thoroughly commingled and consumed with the minimum of residue.

Where a relatively small fire is desired the flow of oil is so regulated that it will drip into the cups or receptacles 18 about as fast as it is consumed, as a consequence these cups or receptacles will not overflow, but

will supply the fuel for the flame passing from the burner. This economizes oil for the reason that it substitutes for a continuous flame or a continuous body of fuel oil extending entirely along the trough or compartment a series of flames or a series of oil receptacles relatively small in size. At the same time the walls of the troughs are not attacked by the flame and are protected from undue and unnecessary corrosion. When, however, it is desired to increase the heat produced by my burner and increase the size of the flame, oil is allowed to flow in greater quantities through the supply tube and flow in such quantities into the cups 18 that it will overflow therefrom and fill the lower portion of the trough as well as the cups. There will then be a body of oil extending over the entire bottom of the trough and around the cups from which the flame will be fed with fuel. I can thus secure by my invention a moderate fire or a heat of as great an intensity as is necessary.

It will be seen that the individual cups or receptacles 18 may be readily detached from the support 19 and replaced by new cups in case they become old or worn out, corroded or otherwise damaged.

It will also be seen that the use of these individual receptacles for a low fire will tend to lengthen the life of the burner as a whole for the reason that the surface of the trough is under these circumstances not subjected to the action of the oil or the action of the flame.

Having thus described the invention what is claimed as new is:

1. A burner of the character described including a supply pipe with dripping orifices, a revoluble member having a plurality of troughs mounted beneath the supply pipe, and a longitudinally extending series of separate receptacles mounted in each trough and adapted to be brought into registry with said orifices.

2. A burner of the character described including a supply pipe with dripping orifices and a revoluble body portion mounted underneath said pipe and including a plurality of troughs, any one of which may be brought into registry with said pipe, and a plurality of separate oil receiving receptacles arranged in each trough, so as to be in registry with the orifices when the trough is in registry with the pipe.

3. A burner of the character described comprising a framework, a body mounted in said framework and formed with a trough, a fuel supply pipe supported in the framework and having a plurality of downwardly opening orifices, an air induction hood formed with an air inlet opening at one end and formed with downwardly and outwardly flared flanges extending over said trough, and a plurality of fuel receiving receptacles sup-

ported in the trough immediately beneath said orifices.

4. A burner of the character described comprising a framework, a revolute body portion mounted in the framework, a plurality of troughs arranged on the body portion, a fuel supply pipe supported in the framework immediately above the body portion and formed with a plurality of downwardly opening orifices, an air induction hood formed with an air inlet opening at one end and having at the other end downwardly and outwardly flared flanges adapted to extend partly over one of said troughs when in registry therewith, and a plurality of separate oil receiving receptacles mounted in each trough in position to register with said orifices.

5. A burner of the character described comprising a supply pipe formed with dripping orifices and a revolute body portion mounted beneath said supply pipe and including a plurality of troughs, any one of which may be brought into registry with said supply pipe, a series of sockets formed in each trough, and a series of separate fuel receptacles smaller than the trough, each receptacle being adapted to engage with one of said sockets, said receptacles being supported thereby in registry with the orifices in the supply pipe when the trough is brought into position beneath said pipe.

6. A burner of the character described, comprising a supply pipe formed with drip-

ping orifices and a revolute body portion 35 mounted beneath said supply pipe and including a plurality of troughs having upstanding sides, any one of which troughs may be brought into registry with said supply pipe, a series of separate fuel receptacles 40 carried in the troughs, but smaller than the same, and being located in registry with the orifices in the supply pipe when the trough is brought into position beneath said pipe, an air induction passage surrounding said 45 supply pipe and discharging around the same against the troughs, and deflecting flanges formed on the lower end of the air induction pipe and extending the length of the body portion and adapted to deflect the 50 flame from said burner laterally toward the sides of the trough supported beneath the air induction hood.

7. A burner of the class described, including a supply pipe with a plurality of dripping orifices, a revolute member mounted beneath the supply pipe, and a plurality of longitudinally extending series of separate receptacles mounted on the revolute member and adapted to be brought into registry 55 with said orifices.

In testimony whereof I affix my signature in presence of two witnesses.
